UNITED STATES PATENT OFFICE.

THOMAS JEFFERSON GOODWIN, OF WACO, TEXAS.

RADIATOR FOR AUTOMOBILES.

1,193,538.

Specification of Letters Patent. Patented Aug. 8, 1916.

Application filed May 22, 1915. Serial No. 29,600.

To all whom it may concern:

Be it known that I, THOMAS J. GOODWIN, a citizen of the United States, residing at Waco, in the county of McLennan and State of Texas, have invented a new and useful Radiator for Automobiles, of which the following is a specification.

This invention has reference to radiators for automobiles, and its object is to provide 10 a radiator which may be readily knocked down or dismantled to facilitate repairs.

Ordinarily automobile radiators comprise two or more series of closely associated pipes or ducts, which after being assembled can 15 only be dismembered with considerable difficulty and the expenditure of a material amount of time. If a leak or some injury requiring repairs occurs in such a radiator in any part except the exterior portions 20 thereof, there is the necessity of separating the radiator into its component parts and this is only accomplished with relatively great difficulty making the repairs to the radiator costly and time consuming.

25 By the present invention the radiator is readily dismantled into a number of large units all parts of each of which are as readily accessible as the exterior portions of the assembled radiator, wherefore all needed 30 repairs may be made quickly and with certainty and in a very small fractional portion of the time required for similar repairs to radiators as ordinarily constructed.

In order to accomplish the purpose intended 35 the radiator is made in a suitable number of sections joined together by union connections, so that by the separation of a very few joints the entire radiator is readily separated into a suitable number of large 40 units every part of each of which may be reached without difficulty and without interference from any of the other parts, because the latter are entirely separated therefrom.

45 The construction also accommodates itself to ample radiating space about the water pipes, and the latter are so proportioned to each other and so arranged that there is an equitable distribution of circulation and this 50 in a far more efficient manner than occurs in radiators as ordinarily constructed. The circulation is evened up by connecting the front of the crown or receiving reservoir of the radiator with a header of suitable size 55 connected by down pipes to another header

of considerably smaller diameter. The rear of the crown reservoir is connected in a readily removable manner with a header of smaller diameter than the front header and the rear header is in turn connected by down 60 pipes to a larger rear header which may be as large as the upper front header. Ordinarily the radiator is provided with an intermediately disposed header connected to the ends of the front and rear headers by 65 union connections and the intermediate upper header is in turn connected by down pipes to a lower header of about the same size, the lower header being in turn connected to the front and rear lower headers 70 by union connections. In this manner the crown reservoir may be permanently attached to the front radiator section made up of the upper and lower front headers and down pipes connecting them, while the intermediate and rear radiator sections are 75 coupled to the front radiator sections by readily separable union connections and the rear end of the crown reservoir is also connected to the rear radiator section by readily 80 removable union connections. By this arrangement the separation of a few union connections permits the dismantling of the radiator into a suitable number of radiator sections, each of which is accessible at all 85 points for repairs or whatever may be needed.

While the invention is particularly adapted for use in connection with automobile radiators, it will be understood that it may 90 be used in other connections wherever the features of the invention are applicable.

The invention will be best understood from a consideration of the following detailed description, taken in connection with 95 the accompanying drawings forming part of this specification, with the further understanding that while the drawings show a practical form of the invention, the latter is not confined to any strict conformity with 100 the showing of the drawings, but may be changed and modified so long as such changes and modifications mark no material departure from the salient features of the invention.

105 In the drawings: Figure 1 is a front elevation of a radiator embodying the present invention, but with the radiator casing omitted. Fig. 2 is an end elevation of the radiator of Fig. 1. Fig. 3 is a section on 110

the line 3—3 of Fig. 2. Fig. 4 is a section on the line 4—4 of Fig. 1. Fig. 5 is a section on the line 5—5 of Fig. 2.

In the showing of the drawings no attempt has been made to illustrate the usual hood or casing inclosing the radiator, nor the usual front grating which may or may not be present, since the invention has nothing to do with these features, and they are more or less common to different types of automobile radiators.

In the structure shown in the drawings the radiator comprises three radiator sections 1, 2, 3, the section 1 being that at the front end of the radiator, the section 3 being the rear section, and the section 2 being an intermediate section. This represents a radiator of customary size, but it will be understood that a less number of radiator sections may be employed, or more than three radiator sections may be employed.

The section 1 comprises a header 4 which may be termed the upper or top header of the section, since it is customary to install the radiator in the upright position. Coupled at one end to the header 4 and extending therealong is a series of down pipes 5 all terminating in another or lower header 6.

The radiator section 2 comprises upper and lower headers 7 and 8, respectively, and connecting down pipes 9, while the radiator section 3 comprises upper and lower headers 10, 11, respectively, and connecting down pipes 12.

The top of the radiator is in the form of a crown reservoir or a distributing chamber 13 into which the heated water from the engine is driven through a pipe or duct 14 by the customary circulating pump, the latter, however, not being shown in the drawings. The water is returned to the water jacket of the engine by way of another pipe 15 connected to the header 11, this being a customary practice in automobile radiator structures. The chamber 13 is provided with the customary filling neck 16 having the usual screw cap closure 17.

The front end of the chamber 13 is provided with an elongated drop portion 18 made fast to the header 4 and extending lengthwise thereof and opening into the header through an elongated port or passage 19. Each end of the header 4 is provided with an elbow 20 and each end of the header 11 has a similar elbow 21, while each header 6 and 10 has respective elbow terminations 22, 23.

Each header 7 and 8 terminates in T connections 24, 25 alined with the elbows 20 and 23 and the elbows 21 and 22. Each elbow 20 is connected to a respective T 24 by a union coupling 26 and other union couplings 26 connect the elbows 23 with the T's 24 and also the elbows 21 and 22 with the T's 25.

The header 10 is connected with the rear portion of the distributing chamber 13 through union connections 27, which in the showing of the drawings are two in number, but it will be understood that one or more may be employed. The chamber 13 is provided with an overflow pipe 28 discharging at a low point and thereby preventing overfilling of the radiator. If it be assumed that the radiator is as full of water as is customary, and the water is being pumped through the radiator by the usual circulating pump, and, furthermore, that the engine is running and is being kept cool by the circulation of the water, the heated water enters the chamber 13 through the pipe or duct 14 and under the impulse of the pump tends to flow toward the front of the chamber where it finds escape through the drop 18 and port 19 into the header 4, and gravitates to the header 6, but the pipes 5 and the header 6 being of smaller diameter than the header 4 to all the pipes 5 with more or less uniformity. The resistance offered by the smallness of the header 6 tends to cause the water entering the header 4 to find escape in other directions, and hence water flows from the header 4 through the elbows 20 to the couplings 24 where the flow is diverted through the header 7 and pipes 9 to the header 8. In the meantime water though in less volume finds its way through the unions 27 to the header 10 and distributing along the latter gravitates through the down pipes 12. The water also finds escape from the header 10 through the elbows 23 to the header 7, distributing along the latter in conjunction with the water finding its way into the header 7 from the header 4, and this water then flows through the down pipes 9 to the header 8. All the water from the headers 6 and 8 finds its way to the header 11 together with such water as enters the header 11 through the down pipes 12 and the water is thereupon drawn from the radiator through the outlet pipe 15 to be forced through the cooling jacket of the engine and ultimately returned to the distributing chamber 13. There is thereby produced because of a distribution of resistance to the flow of water and freedom to such flow, an equality of flow throughout the radiator, so that approximately equal volumes of water are directed through all the radiating pipes of the radiator represented in most part by the down pipes 5, 9 and 12. Because of this the efficiency of the radiator is very materially increased and the engine is correspondingly maintained in a relatively cool condition.

When repairs are needed it is only necessary after having removed the radiator from its casing or hood to disconnect the unions 26 and 27, whereupon the front section 1

with the distributing chamber 18 is readily separated from the middle section 2, and the latter is as readily separated from the rear section 3 of the radiator. Under these circumstances all parts of each section are readily accessible from all sides for inspection and repair, which latter because of the freedom of access may be accomplished in a minimum of time. The radiator may be subsequently reassembled without loss of time, since there is required but the connecting together of a very few union joints and these are all easily accessible from the exterior portions of the radiator. After the radiator is repaired and reassembled it is then readily reintroduced into the hood or casing and connected up to the pump and engine for use.

What is claimed is:—

1. A radiator for automobiles, comprising a plurality of radiator sections each made up of headers and connecting pipes, readily removable couplings between the respective headers of adjacent radiator sections, and a distributing chamber or crown reservoir connected along one edge to a corresponding header and having readily removable connections at the other edge to the corresponding header of another radiator section.

2. A radiator for automobiles comprising a plurality of radiator sections with readily separable circulating connections between the corresponding ends of the radiator sections, and a distributing chamber permanently connected to one radiator section and removably connected to the corresponding portion of another radiator section.

3. An automobile radiator comprising front, rear and intermediate radiator sections, and a distributing chamber therefor constituting the crown of the radiator, said crown being fast to the front radiator section and provided with readily separable circulating connections to the rear section, readily separable circulating connections between the upper ends of the radiator sections, and readily separable circulating connections between the lower ends of the radiator sections.

4. An automobile radiator comprising radiator sections each made up of top and bottom headers and connecting pipes, readily separable circulating connections between the ends of the upper headers, readily separable circulating connections between the ends of the lower headers, a crown or reservoir or distributing chamber fast to and communicating with the upper header of one of the radiator sections, and readily separable circulating connections between the crown reservoir and the upper header of another one of the radiator sections.

5. An automobile radiator provided with a series of circulating radiator sections each having upper and lower headers and con-

nected pipes between them, the upper headers decreasing in diameter toward the rear of the radiator, and the lower headers decreasing in diameter toward the front of the radiator, and a distributing chamber for the top of the radiator connected to the front and rear top headers of the radiator.

6. An automobile radiator provided with a series of circulating radiator sections each having upper and lower headers and connecting pipes between them, the upper headers decreasing in diameter toward the rear of the radiator, and the lower headers decreasing in diameter toward the front of the radiator, and a distributing chamber for the top of the radiator connected to the front and rear top headers of the radiator, said radiator sections having their headers connected together by readily separable circulating couplings, and one of the headers connected to the distributing chamber being similarly coupled thereto.

7. An automobile radiator comprising a front radiator section having a top header, a bottom header, and connecting pipes with the top header of larger diameter than the bottom header, a rear radiator section having a top header and a bottom header with connecting pipes and with the top header of smaller diameter than the bottom header, and a distributing chamber connected at the respective front and rear ends to the top headers of the front and rear radiator sections.

8. An automobile radiator comprising a front radiator section having a top header, a bottom header, and connecting pipes, with the top header of larger diameter than the bottom header, a rear radiator section having a top header and a bottom header with connecting pipes, and with the top blades of smaller diameter than the bottom header, and a distributing chamber connected at the respective front and rear ends to the top headers of the front and rear radiator sections, said radiator also including an intermediate radiator section having top and bottom headers and pipes connecting them with the top and bottom headers each of a size intermediate of the corresponding front and rear headers.

9. An automobile radiator comprising a front radiator section having a top header, a bottom header, and connecting pipes with the top header of larger diameter than the bottom header, a rear radiator section having a top header and a bottom header with connecting pipes and with the top header of smaller diameter than the bottom header, and a distributing chamber connected at the respective front and rear ends to the top headers of the front and rear radiator sections, said radiator also including an intermediate radiator section having top and bottom headers and pipes connecting them

with the top and bottom headers each of a size intermediate of the corresponding front and rear headers, and the radiator sections being also provided with readily separable 5 circulating couplings between them and between the rear radiator section and the distributing chamber.

In testimony that I claim the foregoing as my own, I have hereto affixed my signature in the presence of two witnesses.
